SLUG CASTING MACHINE

Richard R. Mead, Queens Village, N. Y., assignor
to Mergenthaler Linotype Company, a corpora-
tion of New York

Application May 17, 1937, Serial No. 143,002

4 Claims. (Cl. 199—50)

This invention relates to slug casting machines, such as "Linotype" machines of the general organization represented in U. S. Letters Patent No. 436,532, to O. Mergenthaler, wherein a composed line of matrices is presented to the face of a slotted mold between a pair of vise jaws, the mold filled with molten metal to form a slug against the matrices which produce the type characters thereon, and the slug thereafter ejected from the mold between a pair of trimming knives which trim the lateral faces of the slug prior to the depositing of the later in the galley.

More particularly, the present improvements deal with devices whereby the printing edges of the slugs beyond the type characters thereon may be cast at a predetermined level below the printing face of the type characters, in order that a zinc or other form of printing plate containing 15 cuts or the like (which must stand at the same type height as the characters on the slugs when assembled or made up in the printing forms) may be mounted directly on the slugs, thereby avoiding the necessity of milling off or otherwise reducing the height of the blank portions 20 on the slugs to bring them to the proper height for such purpose.

In carrying out the invention, the vise jaws, which are arranged to be moved inwardly, to 30 close the mold slot at the opposite ends of a composed line, are equipped each with a rib adapted to extend into the mold slot a distance sufficient for the accommodation of the zinc or cut to be used. In the specific embodiment illustrated, the 35 mold slot near the front, is formed in its upper side wall with a face flaring outwardly and upwardly, and the ribs which are adapted to enter the mold slot are formed on their upper edges with correspondingly sloped surfaces, so that 40 when the mold is moved forwardly into contact with the composed line, the ribs will enter the mold slot freely and then be cammed or wedged downwardly by the engagement of the angularly disposed surfaces until the bottom edges of the 45 ribs, which are horizontal, are caused to engage tightly with the lower side wall of the mold slot.

The ribs extend the full length of the vise jaws and project into the mold slot by an amount equal to the distance that the depressed portion 50 of the slug is intended to stand below the base of the type characters.

Preferably, the mold entering ribs are carried by plates detachably secured in the vise jaws in much the same manner as described in my co-pending application, Serial No. 81,394, filed May

23, 1936, in order that they may be readily removed and replaced by other ribs capable of co-operating with molds of different sizes. The detachable plates have a loose or floating fit in the jaws, so that, as the mold is moved forwardly into contact with the line, the angularly disposed surface of the mold, by its cooperation with the similarly disposed angular surfaces of the ribs of the floating sections, will align the ribs accurately with the mold slot and bring about the metal tight engagement required. Likewise, as described in my co-pending application, a metal tight engagement at the ends of the mold slot is secured by providing the intermediate liners which, as usual, space the body portion of the mold from the cap, with narrow ribs at their inner edges adjacent the mold slot and which engage tightly against the outer faces of the ribs associated with the vise jaws.

The means herein disclosed for bringing about the lateral movement of the ribs to effect their metal tight engagement with the mold are given merely by way of example, and other means for effecting the same result could be employed with equivalent efficacy, the essence of the invention 20 residing in the employment of floating ribs with horizontal edges for sealing engagement with the adjacent side wall of the mold slot.

Referring to the drawing:

Fig. 1 is a horizontal sectional view through the mold and the vise jaws, showing the mold in engaging relation with the jaws;

Fig. 2 is a vertical section through the mold disc at the end of the mold, and showing the latter in partial section in engaging relation with 35 a line of matrices and the vise jaws;

Fig. 3 is an end view of the mold, partly in section, and with the vise jaw in full section, the parts being illustrated immediately as the rib is starting to enter the mold slot during the forward movement of the mold into contact with the 40 jaws; and

Fig. 4 is a vertical sectional view through the mold and the vise jaw when the mold is in its extreme forward position with the rib fully entered therein.

As usual, the composed line of matrices X is presented between a pair of vise jaws A and B and in front of a slotted mold C, which latter has previously been located in casting position by 50 a quarter rotation of a mold disc D on which the mold is mounted. When a slug is to be cast with a low quad or depressed portion for the accommodation of a zinc plate or cut, the line of matrices will, of course, be of less than full length, 55

and accordingly, one or both of the jaws will be moved inwardly until arrested by contact with the ends of the line, depending upon whether the depressed portion of the slug is to be formed at one end or the other or at both ends of the slug. In other words, the improvements are particularly applicable to a machine equipped with a quadding and centering mechanism.

The improved mold comprises a lower body portion C¹ and an upper cap portion C², which portions present, respectively, opposed faces c and c¹ defining the side walls of the mold slot, and a pair of intermediate liners C³, whose opposed faces define the end walls of the mold slot. Adjacent the front, the mold slot is formed with a face c² flaring outwardly and upwardly and which terminates at its rear edge substantially on a line corresponding to the low quad or depressed blank portion of the slug. The liners C³ at the front terminate rearwardly of the mold face and also somewhat rearwardly of the line of intersection of the flaring face c² with the straight face c¹; and moreover, the liners, adjacent their inner faces, are formed with forwardly projecting lips C⁴, the outer edges of which are relatively narrow and terminate at the aforesaid line of intersection. The purpose of the lip portions of the liners is to secure a metal tight engagement at the ends of the mold slot, as will be more evident as the description of the invention proceeds. In other respects, the mold is the same as usual, being equipped with a pair of grooves C⁵ and C⁶, the upper surfaces of which cooperate with the lower projecting ears on the casting edges of the matrices during the alinement of the latter with the mold slot.

After a line has been located at the casting level, the vise jaws, singly or conjointly, depending upon whether the machine is set for a quadding or a centering operation, are moved inwardly until arrested by contact with the ends of the line. In Fig. 1, there is illustrated a condition wherein the machine is set for quadding with the right hand jaw. Thereafter, the mold C moves forwardly and the matrices alined with the mold slot by the engagement of their lower ears with one or the other of the alining surfaces presented by the grooves C⁵ and C⁶, depending upon whether the matrices are composed at the upper or lower level. That part of the mold slot left uncovered by the composed line is closed by a rib E formed on a plate E¹ with which each of the vise jaws is equipped.

As shown in Figs. 2 to 4, the ribs E are formed each with an upper face e disposed angularly with respect to the inner face of the jaw, a lower horizontal face e¹, and a vertical rear face e². As will be seen (see Fig. 3), the ribs E, in the normal position of the parts, are disposed slightly above the lower side wall c of the mold slot in order that there will be sufficient clearance between the surfaces of the ribs and mold slot for the ribs freely to enter the mold slot. This clearance, however, is not so great as to locate the upper edges of the rear vertical surfaces e² of the ribs E above the outer upper edge of the flared mold slot, and hence there will be no difficulty in effecting an entrance of the ribs E into the mold slot as the mold is moved forwardly into contact with the composed line.

The plates E¹ on which the ribs E are located have a free or floating fit with the vise jaws, so that, as the mold is moved forwardly into contact with the jaws, the angular surface c² on the top wall of the mold slot will engage the angular

surfaces e on the top edges of the ribs E and, since these surfaces are disposed at the same angle with respect to the face of the jaw, will cam the ribs downwardly from the position shown in Fig. 3 to the position shown in Fig. 4, thereby effecting a metal tight engagement between the bottom horizontal surfaces e¹ of the ribs E and the bottom side wall c of the mold slot. The engagement of the angular surfaces c² and e¹ will likewise produce a metal tight fit between them, the rib E extending into the mold slot to the line of intersection between the angular surface c² and the straight surface c¹ of the mold slot.

The mounting of the plates E¹ on which the ribs E are presented will now be described and, since they are the same for both jaws, except for one being left and the other right, the description herein will be confined to one only.

As shown in the figures, the plate E¹ extends the full length of the vise jaw and is contained within a recess B¹ formed in the rear or casting face of the jaw, it being understood that during the casting operation, the rear face of the plate is substantially flush with the rear face of the jaw. At the bottom of the recess B¹, the jaw B is formed with a second longitudinal recess B², which, in suitable spaced relation, presents relatively short dove-tail grooved portions B³. These dove-tail grooved portions are adapted to receive dove-tail tongue portions E² formed on the inner or rear face of the plate E¹. According to this construction, the plate E¹ may be attached to or detached from the jaw B by a slight endwise movement in opposite directions, the dove-tail tongue portions being adapted to enter the dove-tail grooved portions by an endwise movement of the plate in a direction away from the line clamping face of the jaw, and being adapted to leave by a similar movement in the opposite direction. In this connection, it is pointed out that the dove-tail grooved portion B³, nearest the line clamping face of the jaw, is arranged at such a distance from said face that, when the plate E¹ has been attached to the jaw in the manner just described, its inner or line engaging end will be flush with that face of the jaw, as shown in Fig. 1.

The positioning of the plate E¹ within the recess B² is determined by a stop pin B⁴ which is arranged to engage the outer end of the dove-tail tongue portion E² located nearest the outer end of the jaw when the plate is attached to the jaw (see Fig. 1). The plate is then locked in this position by ball detents B⁵ arranged at the base of the recess B² and adapted to snap into holes or depressions E³ formed in the dove-tail tongue portions E² of the plate. It will be understood that these ball detents, while exerting enough tension to hold the plate E¹ in place, will yield readily when the plate is shifted endwise to detach it from the jaw and also when the plate is moved downwardly during the camming down action of the rib E in the mold slot. When the mold recedes from the jaw after a casting operation, the detents B⁵ will act to raise the plate E¹, and consequently the rib E, to normal position, wherein the latter is again ready to enter the mold slot during a succeeding casting operation. In effect, the plate E¹ has a free casting operation, the detents B⁵ will act to raise the plate E¹, and consequently the rib E, to normal position, wherein the latter is again ready to enter the mold slot during a succeeding casting operation. In effect, the plate E¹ has a free fit in the vise jaw, so that it may partake of what, in effect, is a universal movement.

The invention, in its broadest aspects, contemplates a mold slot wherein one of the side

walls extends uniformly out to the face of the mold, and wherein the other side wall is formed near the front with a portion of its surface offset, so as to permit a rib adapted to produce a low 5 quad portion on the slug freely to enter the mold, and with the provision of means for displacing the rib laterally thereof in order to effect a metal tight seal between one surface of the rib and that side wall surface of the mold slot which extends 10 uniformly out to the face of the mold.

In the accompanying drawing, the invention has been shown merely by way of example and in preferred form, and obviously many variations and modifications may be made therein which 15 will still be comprised within its spirit. It is to be understood, therefore, that the invention is not limited to any specific form or embodiment, except insofar as such limitations are specified in the appended claims.

20 Having thus described my invention, what I claim is:

1. A slug casting machine including, in combination, a slotted mold having one of its side walls formed with a bevelled surface extending 25 inwardly from the mold face throughout the length of the mold and having its other side wall extended straight from the mold face, said mold also having an end wall whose front face is set 20 back with reference to the mold face and extends parallel thereto, a vise jaw adjustable to different positions longitudinally of the mold and provided with a freely mounted mold slot entering element having a casting face parallel to the front 30 face of said end wall and adapted to make sealing contact therewith in any adjusted position of the jaw, said element throughout its length having a bevelled surface complementary to that on one of the side walls of the mold as well as another surface parallel with the other straight side wall of the mold, said complementally bevelled surfaces cooperating as the entering element moves into the mold slot to urge said element laterally thereof to effect a metal tight seal 35 between the parallel surface of said element and the straight side wall of the mold, and means for returning the mold slot entering element to normal position subsequent to each casting operation. 40

tering element moves into the mold slot to urge said element laterally thereof to effect a metal tight seal between the parallel surface of said element and the straight side wall of the mold.

2. A combination according to claim 1, including 5 means for returning the mold slot entering element to its normal position on the vise jaw subsequent to a casting operation.

3. A combination according to claim 1, wherein the vise jaw is provided with means for returning the mold slot entering element to its normal position thereon subsequent to a casting operation. 10

4. A slug casting machine including, in combination, a slotted mold having one of its side 15 walls formed with a bevelled surface extending inwardly from the mold face throughout the length of the mold and having its other side wall extended straight from the mold face, said mold also having an end wall whose front face is set 20 back with reference to the mold face and extends parallel thereto, a vise jaw adjustable to different positions longitudinally of the mold and provided with a freely mounted mold slot entering element having a casting face parallel to the front 25 face of said end wall and adapted to make sealing contact therewith in any adjusted position of the jaw, said element throughout its length having a bevelled surface complementary to that on one of the side walls of the mold as well as another surface parallel with the other straight side wall of the mold, said complementally bevelled surfaces cooperating as the entering element moves into the mold slot to urge said element laterally thereof to effect a metal tight seal 30 between the parallel surface of said element and the straight side wall of the mold, and means for returning the mold slot entering element to normal position subsequent to each casting operation. 35
